BLOUSE HOLDING WEIGHT FOR TROUSER LEGS

Robert H. Allan, Jr., Kansas City, Mo.

Application June 27, 1951, Serial No. 233,807

1 Claim. (Cl. 2—232)

This invention relates to a device for use with an article of clothing to hold the same in a desired shape or configuration and to thereby maintain a regulation or customary appearance without the necessity of attention on the part of the user.

It is common knowledge that present day uniforms for servicemen include boots that are adapted to receive the lowermost portions of the trouser legs therewithin. Such manner of wearing the trousers and the boots is required and additionally, such wearing apparel must be maintained neat and orderly with the trousers boused over the uppermost edges of the boots. Such blouses are necessary because of the fact that they provide for freedom of movement in sitting, standing and other positions, on the part of the wearer, but as such positions are assumed, the blouses themselves become disarranged and unsightly. This necessitates forming and rearranging of the blouses each time the wearer rises from a sitting position and at other times even while walking, resulting in an aggravating problem at all times.

It is the most important object of the present invention therefore, to provide a holding means for the blouses taking the form of a weight that is actually disposed within the blouses around the leg of the wearer and capable of maintaining such bousing at all times, irrespective of the various positions assumed during use.

Another object of this invention is the provision of a weight as above set forth that is formed of a number of relatively movable sections, so that the same is always in a blouse-holding position and capable of adding no discomfort whatsoever to the wearer.

A still further object of this invention is the provision of a blouse-holding device constituting a chain or chain-like weight composed of a number of interconnected links, tubes joined by a continuous flexible band and/or a continuous flexible tube, solid metallic or mineral elements disposed within the aforesaid tube and threaded upon a continuous band if desired or separated by partition or spacer members, or a filling of granular material within a continuous tubular member to present a continuous leg-encircling device and having, if desired, a fabric covering therefor.

In the drawing:

Figure 1 is an elevational view of a pair of boots showing one form of the aforesaid trouser legs therewithin, and the blouses thereof, parts being broken away to reveal the disposition of the holding means hereof.

Fig. 2 is an elevational view partially in section illustrating the holder of Fig. 1 in place around the leg of the wearer.

Fig. 3 is a perspective view of the blouse-holding weight for trouser legs shown in Figs. 1 and 2, parts being broken away for clearness; and

Figs. 4 to 7 inclusive are perspective views of modified forms of blouse-holding weights for trouser legs made pursuant to my present invention, parts being broken away to reveal details of construction.

One customary manner of wearing boots with trousers

2

is illustrated in Figs. 1 and 2 of the drawing wherein the legs 10 of such trousers, extend into the uppers 12 of boots 14. Obviously, the lowermost, marginal edge 16 of the trouser legs 10 may project a considerable distance 5 into the boot uppers 12 but the blouse thus formed will obviously become disarranged or pull out the moment the wearer sits down or assumes positions other than the erect, upstanding position illustrated in Figs. 1 and 2. Accordingly, considerable material must be reserved in the trousers 10 outside the boot 14, to provide full freedom of movement and normally, such excess material takes the form of a blouse 18 that overlaps a portion of the uppermost edge of the boot uppers 12.

Maintenance of this blouse 18 in a neat, orderly fashion, presents the problem above indicated to which this invention is directed. There is provided a holding means in Figs. 1 to 3 inclusive broadly designated by the numeral 20 for each trouser leg 10 respectively, and since the same are identical, only one will be described.

The holder or weight 20 is continuous and will be normally substantially circular when placed in use in circumscribing relationship to the leg 22 of the wearer. In order that the device 20 performs its function of holding the blouse 18 without added discomfort to the wearer, it is preferably made of a number of relatively shiftable, interconnected sections and to this end, a chain-like, continuous band 24 is provided including a number of interconnected links 26. It is contemplated that all of the links 26 be joined together but if desired, one of such links may be releasable in any suitable conventional manner.

A covering 28 that is tubular and also continuous, is provided for the chain 24 and such covering is preferably made from fabric material that may advantageously be the same as that forming the trouser legs 10 and may be of the same color as the material forming trouser legs 10.

The size of the individual links 26 is of no significance other than the fact that the same should be as light as possible, yet sufficiently heavy to hold the blouse 18 in place when the device 20 is placed in use. Furthermore, it is contemplated that each link 26 be of such material or be provided with a coating of substance that will resist rust and other corrosion. The covering 28 for the links 26 will prevent annoyance due to any rattling or noise that might otherwise accompany the use of the chain 24 and will additionally protect the trouser legs 10 if for some reason the links 26 do become corroded and tend to discolor the trouser legs 10.

The device 20 is placed in use in the manner illustrated in Figs. 1 and 2 of the drawing, and as shown, is disposed within the trouser legs 10 in circumscribing relationship to the leg 22 and particularly in surrounding relationship to the boot upper 12 adjacent the upper edge thereof. It is seen that the device 20 engages only the material from which the trouser legs 10 is made and does not come into contact with leg 22 or any part of the boot 14.

The diameter of the continuous weight 20 should be chosen to fully circumscribe the boot upper 12, be generally of the same circumference as the trouser blouse 18, yet not be so tight as to cause discomfort or to adversely affect the primary function thereof in holding the trouser leg 10 boused as at 18. The ring-like weight may be mounted in place by first applying the same to the leg 22 prior to placing of the trouser leg 10 into the boot upper 12 as at 16 and thereupon be caused to gravitate along the leg 22 into its operative position within blouse 18 as indicated in Figs. 1 and 2 of the drawing.

It is seen that while the chain-like weight 20 is fully capable of maintaining the blouse 18 in the trouser legs 10 at all times, it will not interfere with the user so far

as assuming any desired position, and will yield during sitting and automatically resume its illustrated position as soon as the wearer rises, and during walking.

So far as appearance is concerned, the device 20 is not seen from the outside and its presence cannot be known except so far as its advantageous use in presenting a neat appearing blouse 18 in each trouser leg 10 respectively as is desired and customary, as well as is required by the rules and regulations of the armed services.

The devices illustrated by Figs. 4 to 7 inclusive are placed in use in the same manner as weight 20 in Figs. 1 to 3 inclusive and therefore, the manner of construction only of the modified devices will be set forth.

Weight means 40 in Fig. 4 of the drawings, includes a continuous tubular covering 42 of flexible material similar to covering 28, having therewithin a plurality of lightweight tubes 44 and a number of shorter and heavier tubes 46, all threaded on a continuous band 48. The tubes 44 may be made from wood or other lightweight material capable of eliminating the possibility of any disturbing noise that would otherwise be likely if the tubes 44 and 46 were all of metal or similar material. The cylinders 46 on the other hand are preferably made from metal or a mineral such as ceramic substances and the band 48 may consist of a strong and durable cord or suitable flexible cable.

It is clear that in the device shown by Fig. 4, either the tubular covering 42 or the band 48 may be eliminated if desired since either is capable of holding the elements 44 and 46 in a continuous loop. Here again, as in the case of the chain 24, the band 48 may be provided with releasable structure or manufactured in a continuous loop.

The modification illustrated by Fig. 5 of the drawings is broadly designated by the numeral 50 and includes a continuous tubular covering 52 similar to tubes 28 and 42 and adapted to receive a plurality of weights 54. The weights 54 are held apart and therefore against rattling by means of transverse lines of stitching 56 presenting a number of pockets 58. Each pocket 58 may contain an element 54 if desired or certain of the pockets 58 may be left blank as illustrated. Elements 54 may be spherical as illustrated, oblong, or of any other suitable configuration. Here again, the material forming the elements 54 may be chosen to suit the desires of the manufacturer and metal or mineral is suggested.

The device shown by Fig. 6 of the drawings is designated by the numeral 60 and includes a tubular flexible covering 62 having a plurality of weight elements 64 therein-spaced by discs or the like 66 to prevent contact of the elements 64 with each other and thereby eliminate rattling. The spacer 66 may be made from felt or other means of absorbing noise and the elements 64 may be much the same as elements 54 in Fig. 5. Here again,

tubular sleeve 62 may be eliminated and the elements 64, as well as the washer-like spacers 66, threaded upon a band such as at 48 in Fig. 4 of the drawings, or, such band may be provided in the modification of Fig. 6 in addition to the sleeve covering 60.

The modification shown by Fig. 7 of the drawings is broadly designated by the numeral 70 and includes a tubular, flexible container 72 for receiving a filling 74 of granular material such as buckshot, aggregate or the like.

It is now clear that in all forms of the present invention, a continuous weight taking the form of a loop or ring is provided for holding a blouse such as at 18 in its desired configuration, and while many additional modifications and combinations may be presented, it is desired to be limited only by the spirit of the invention as defined by the scope of the appended claim.

Having thus described the invention what is claimed as new and desired to be secured by Letters Patent is:

In combination, a boot provided with an upper; a pair of trousers having a leg extending into said upper when the boot and the trousers are placed in use, said trouser leg overlapping a portion of said upper to present an upwardly facing, continuous cavity in said leg surrounding the upper adjacent to and immediately below the uppermost end of the upper; a continuous, circular ring having a diameter greater than the diameter of the upper and disposed in the cavity in complete surrounding relationship to the upper, said ring being circular in cross-section to maintain a blouse in said leg of substantially U-shaped cross-sectional configuration and including a weight composed of a continuous chain having a plurality of interconnected metallic links whereby the ring will remain in the cavity by force of gravity; and a continuous, circular, tubular covering enclosing the ring, said cover being separate from the leg whereby the ring may be removed from within the cavity upon removal of the leg from within the upper, and whereby the ring is free to move with the blouse as the latter shifts relative to the upper.
